SPRING SEAT CONSTRUCTION

George M. Markle, Grand Rapids, Mich.

Application September 2, 1954, Serial No. 453,854

2 Claims. (Cl. 155—179)

This invention relates to the construction of spring seat units of the type used in automobiles and other vehicles. Conventionally, these units are formed of a combination of bent wire and sheet metal, and establish a base for the usual upholstery. They are normally subjected to rather hard usage, and yet must provide a maximum of comfort for a given space requirement. A soft resilient spring action requires a considerable amount of space for the deflection of the spring, and the effective utilization of available space to give the maximum of "softness" for a given allowable unit thickness is an objective which is almost always present in the design of this type of structure. This invention provides an unusual amount of resilience for a given unit height through the use of a novel spring action, and yet provides this action with a wire formation of noteworthy simplicity, and formed in such a manner that the assembly of the entire spring unit is simplified.

Another important feature of this invention is the provision of lateral and diagonal bracing which serves to stabilize the spring unit, and yet perform this function with sufficient resilience that distortion does not develop as the spring unit deflects under load. The stabilization afforded by this construction not only prolongs the life of the spring unit itself, but similarly preserves the integrity and appearance of the upholstery.

An important aspect of this invention is the provision of a series of spring units centering around coils disposed with their axis horizontal. This is in contrast to the conventional vertical coil arrangement, and the spring action provided by applicant's invention is generated by the angular deflection of one end of the coil with respect to the other rather than by a compression of the coil itself. In the preferred form of the invention, the spring action is generated by a spring unit formed of a single continuous piece of bent wire, the opposite ends of which are secured to a border or frame member. These spring units are several in number, and are spaced across the unit. They extend from front to rear, and in themselves constitute a bridge which does not need intermediate supporting structure in the nature of an extensive frame work. The central portion of these spring elements is preferably arch-shaped and approximately the contour of the conventional upholstered seat. The rearward extremity of this arched portion terminates in a coil, and the projecting end of this coil is suitably formed for securing to the frame or border portion. The front portion of the arch-section likewise terminates in a coil, which may be termed the upper front coil. The wire extending from that coil is inclined downward and rearward, and a second coil (which may be termed the lower front coil) is formed at a position below and somewhat behind the upper front coil. The wire continuing from this coil extends forward to the point of attachment with the lower front border or frame member. It is interesting to note that this spring formation provides a hinge-type resiliency at the rear coil, and for a "knee-action" deflection at the forward end. A given amount of load placed at the middle portion of the central arch will therefore generate a torsional resiliency at the rear springs

2

and also create torsional deflection of the front coils accompanied by a considerable amount of vertical displacement of the upper front coil with respect to the lower. The rear of the spring unit will have a very small amount of fore-and-aft deflection due to the presence of the single rear coil; and the movement of the arch is similar to the movement of a radius arm about a pivot point. Such rotation tends to generate a slight degree of forward movement of the upper front of the spring unit, and this action controls the tendency of the lower front coil to move downwardly below the plane of the frame portion. It will be appreciated that if the upper front of the arch were to be artificially given a forward motion such motion would be accompanied by an upward movement of the lower front coil. To some extent, the point of attachment of the front spring unit to the frame may be selected to give a balanced action such as will minimize the amount of deflection at the point of attachment to the frame. This feature is extremely valuable in preventing breakdown of the spring unit as the result of continued use.

The several spring units are connected by front and rear border wires preferably through the use of clips which engage a considerable length of both of these components, and thereby permit a much more secure fastening. Preferably the spring units are enclosed in an envelope of fabric, and a series of transverse load distribution members are provided which extend across the width of the spring unit and are spaced from each other from front to rear. These members are laid over the fabric in order to prevent chafing against the spring units, and they are provided with the plurality of coils arranged to lie flat against the fabric, the coils permitting the lateral resilience necessary when load is placed at a particular point on the seat unit.

Diagonal bracing preferably extends from the upper side edges of the seat unit diagonally to a member fixed with respect to the lower frame. The provision of a coil in these members provides a sufficient amount of resilience to remove the tendency of a diagonal brace to distort the spring unit sideways as downward deflection takes place. In this manner, the fixed action of a radius arm gives way to a resilient biasing action which provides a continuous tendency to restore the spring unit to its original condition after load is removed.

The several features of this invention will be analyzed in detail through a discussion of the particular embodiments illustrated in the accompanying drawings.

Figure 1 illustrates a perspective view of an assembled spring unit, with a portion of the fabric removed to show the interior construction.

Figure 2 is a section on an enlarged scale showing the forward portion of the unit, and illustrating the deflection movement of the springs.

Figure 3 is a section taken from plane III—III of Figure 2.

Figure 4 is an enlarged view of the junction of a spring member with the frame.

Referring to the drawings, the spring seat unit includes a relatively fixed base or frame formed by the lower front border member 10, the lower rear border member 11, and the lower side members 12 and 13. These are preferably formed of bent sheet metal crimped into assembled relationship as shown. A series of beams 14 through 18, inclusive, are also preferably formed of sheet material and are secured at their front and rear ends to the border members 10 and 11, respectively. The upper front and upper rear border wires 19 and 20 are offset at spaced locations along their length to securely position the front clips 21 and the rear clips 22 which secure the upper portions of the spring elements

23 in position. A sheet of fabric 24 is laid over the assembly of spring units, frame, and border wires, and lateral load-distribution members 25, 26, 27, and 28 are positioned on top of the fabric to prevent chafing under vibration and wear. The lateral members are secured with respect to the sides of the seat unit through the use of clips as indicated at 29 through 36, inclusive. Each of the lateral members are provided with a series of coils as indicated at 37 which lie against the fabric 24, and permit a considerable amount of stretching as the spring unit is locally deflected.

Resilient diagonal bracing members 38 and 39 are provided to establish a tendency to return the spring unit into its original erect position after an eccentric load has been removed. Coils as indicated at 40 and 41 in each of these diagonal braces provide resilience rather than a positive radius action which would deflect the spring unit laterally as load was applied. The upper ends of these diagonal braces are connected to the ends of the seat unit with the clips 42 and 43, respectively, and the lower ends are crimped as shown into engagement with the beams 15 and 17.

The spring elements which contribute the resilience to the assembled unit shown in Figure 1 are each prefabricated of a continuous piece of bent wire 44. (Refer to Figure 2.) Each of the elements may be considered as including a rear coil 45 (which has its end 46 in engagement with the lower rear frame member 11), an arched portion 47, an upper front coil portion 48, a lower front coil portion 49, a coil-connecting portion 50, and an extension 51 of the material forming the coil 49 which proceeds forward to a point of attachment with the lower front frame 10. The arch portions of the spring elements at the opposite ends of the spring assembly may be considered as forming a part of the upper frame or border wire.

In Figure 2, the full-line representation illustrates the seat unit in the erect or un-deflected condition, while the dotted lines show the unit after load has been applied. There are several important relationships to be noted as the spring elements move from one position to the other. The downward movement of the lower front coil 49, below the level of the side frame member 12 is indicated at 52, and must be carefully controlled so that it does not interfere with the other structure on which the seat is mounted. To a very considerable extent, the action of the rear coil 45 is similar to that of a hinge resulting in a radius-like movement of the arch portion 47, and creating some extent of forward movement 53 of the upper front coil 48 during deflection. The general direction of movement of this coil during deflection is approximately as indicated by the arrow 54. The forward movement of the coil 48 may be such in particular installations as to bring it ahead of the lower front frame member 10 by the amount indicated at 55. It should be noted that this dimension may be selected to give a balance of forces between the coils 48 and 49 such as would tend to reduce the displacement 52. As the upper front coil 48 continues to move forward (or as the dimension 55 tends to increase), the lower coil 49 tends to be more positively positioned so that the downward movement thereof is reduced. The forward movement of the coil 48 during deflection has an important tendency to maintain the elevation of the coil 49, since such forward movement tends to generate a moment about the point of attachment of the spring end 51 to the lower frame member 10 such as will cause the coil 49 to move upwardly. This tendency can be balanced in particular installations with the natural downward tendency due to spring deflection so that the dimension 52 may be controlled as desired.

In particular installations, it may be desirable to supplement the ability of the rear coils to act as a "hinge" by the utilization of fore-and-aft resilient diagonal bracing as indicated at 56. This bracing may be formed

and secured in generally the same manner as the diagonals 38 and 39.

Referring to Figure 4, the attachment of the extensions 51 (of the spring element) to the frame must allow for the fact that a tendency for relative rotation is likely to take place between these components. The forward ends of the extensions 51 are bent into parallelism with the frame 10 at 57, and a return bend 58 creates a U-shaped configuration, with the frame being crimped together at 59 between the extensions 51 and the portion 58 to hold the sections 57 in engagement with the frame. Lateral shifting in either direction of the extensions 51 is prevented in this manner, and the frame is given a double grip to more effectively resist excessive deflection. For small degrees of deflection, the sections 57 act somewhat in the manner of a hinge pin.

The particular embodiments of the present invention which have been illustrated and discussed herein are for illustrative purposes only, and are not to be considered as a limitation upon the scope of the appended claims. In these claims, it is my intent to claim the entire invention disclosed herein, except as I am limited by the prior art.

I claim:

25 1. A spring seat construction, comprising: upper and lower front and rear continuous border members disposed substantially one above the other and defining the edges of a spring assembly, said upper border members having offset portions; a plurality of spaced spring members extending from front to rear of said spring assembly and including a rear coil portion, an arch portion, an upper front coil portion, and a lower front coil portion, said spring members each being formed of continuous wire having the ends thereof respectively connected to said lower front and rear border members, and said upper front and rear border members being secured to said arch portions with clips engaging said upper front and rear border members respectively at said offset portions; resilient diagonal means having the ends thereof fixed respectively to said upper and lower border members, and including intermediate coil portions; and resilient transverse members secured exclusively to the outermost of said arch members and extending across and supported by said arch portions, each of said transverse members having a plurality of coil means.

2. A spring seat construction, comprising: upper and lower front and rear continuous border members disposed substantially one above the other and defining the edges of a spring assembly; and a plurality of spaced spring members extending from front to rear of said spring assembly and each including a rear coil portion, an arch portion, an upper front coil portion, and a lower front coil portion, said spring members each being formed of continuous wire having the ends thereof respectively connected to said lower front and rear border members, and said upper front and rear border members being secured to said arch portions with clips engaging said upper front and rear border members respectively.
